ICE BUCKET OR THE LIKE

Marten Gottsegen, Chicago, Ill., assignor to Gotham
Industries, Inc., Chicago, Ill., a corporation of New York

Filed Sept. 6, 1962, Ser. No. 71,575

Term of patent 14 years

(Cl. D44—15)

—F 1 — 1

—F 1 — 2

—F 1 — 3

FIG. 4FIG. 5FIG. 6FIG. 1 is a front elevational view of an ice bucket or the like, embodying my new design;

FIG. 2 is a rear elevational view thereof;

FIG. 3 is a top plan view thereof;

FIG. 4 is a side elevational view thereof;

FIG. 5 is a side elevation as viewed from the opposite side; and

FIG. 6 is a bottom plan view thereof.

I claim:

The ornamental design for an ice bucket or the like, substantially as shown.
